UNITED STATES PATENT OFFICE.

CHARLES F. STODDARD, OF NEW YORK, N. Y., ASSIGNEE TO AMERICAN PIANO COMPANY, OF NEW YORK, N. Y., A CORPORATION OF NEW JERSEY.

AUTOMATIC MUSICAL INSTRUMENT.

1,409,482.

Specification of Letters Patent. Patented Mar. 14, 1922.

Application filed December 11, 1918. Serial No. 805,399.

To all whom it may concern:

Be it known that I, CHARLES F. STODDARD, a citizen of the United States, and a resident of New York, county of New York, State 5 of New York, have invented an Improvement in Automatic Musical Instruments, of which the following description, in connection with the accompanying drawings, is a specification, like characters on the drawings representing like parts.

This invention relates to automatic means for playing musical instruments such, for instance, as pianos; and pertains more particularly to means for governing and varying 15 tone intensities.

Among other objects, the invention is intended to provide apparatus capable of producing a great variety of variations in intensity of playing, such apparatus comprising 20 preferably, though not essentially, a combination of means for producing crescendo and decrescendo effects and also instituting various defined grades or steps of playing intensity. For these purposes the invention 25 may be embodied in apparatus which is very simple and reliable in operation.

For illustration, the accompanying drawing shows one practicable embodiment of the invention employing suitable pneumatically 30 governed devices in cooperation with a piano action; but, as will appear to those skilled in the art, the invention is susceptible of embodiment in various constructions and organizations other than that particularly 35 shown and described herein. It will appear likewise that it is not indispensable that all the features of the invention be used conjointly, since their respective substantial advantages may accrue from their separate application in any practicable manner to a suitable 40 playing instrument.

In the drawings:

Fig. 1 is a diagrammatic representation of a typical piano action, with operating and 45 governing means exemplifying the application and utility of the invention;

Fig. 2 is a diagrammatic representation of a perforated note sheet such as may be used in cooperation with the apparatus of Fig. 1.

Referring to the drawing, a typical piano 50 action shown in its normal position of rest comprises a key-controlled sticker B to act upon a wippen I, a hammer C, damper E,

string D and other parts which may be those well-known in the art. To operate the action 55 pneumatically, a motor pneumatic F is provided, having a sticker H to act upon the wippen I. A wind trunk 7 leads to the wind chest for the motor pneumatics, each of which has a secondary valve 8 controlled by 60 a primary valve 9 operated from a trackerboard G through a duct 10, in the usual manner.

The trunk 7 communicates with a regulated exhaust chest 12, which may be of any 65 practicable construction. A high exhaust chest 14, arranged for communication with the chest 12, may be connected by a trunk 15 with any source of pneumatic exhaust, such as feeder bellows of any practicable 70 type.

For the purpose of explaining the general character of this invention, and to exemplify one practicable manner of governing tone intensities, I have selected the apparatus of 75 the drawings in which the striking pneumatics F are caused to operate by the regulated exhaust in the chest 12, this regulated exhaust being varied, in order to vary the operation of the striking pneumatics, by 80 subjecting it more or less to the influence of the high exhaust in the chest 14. For these specific purposes I have provided, between the high exhaust chest 14 and the regulated exhaust chest 12, a port 30, controlled by a 85 throttle valve 31.

This valve 31 may be operated by a variety of different means. In this specific apparatus, the stem 32 of the valve 31 is connected to a movable board 33 of a bellows apparatus 90 presently described, said board being hinged at 33a.

Beneath the board 33 are three pouches 34, 35, 36, having their upper boards secured to the common movable board 33 and their 95 lower boards secured to a fixed plate 36a as shown. The pouches may be made adjustable toward and from the hinge 33a, to vary their leverages, in any practicable manner as by having their upper and lower boards, 100 secured by screw and slot connections to the movable board 33 and lower supporting plate respectively.

Another pouch 37 has its lower board secured to the movable board 33 and its upper 105 board to a stationary plate 38. A condition

of partial exhaust is maintained at all times in the pouch 37 as presently described. The degree of exhaust in the pouch 37 may be varied; but for the present this capacity may 5 be neglected and the pressure within the pouch acting upon the board 33 may be considered uniform.

Thus, the pressure in the pouch 37 being always less than atmospheric pressure, said 10 pouch in effect exerts continuously an upward pull upon the board 33, contributing to control the valve 31.

Ducts 40, 41 and 42 enter respectively the pouches 34, 35 and 36. Each duct is controlled (as hereinafter explained) so as to admit to its pouch either atmospheric pressure, or regulated pressure from the chest 12; and the regulated pressure may be admitted to any one or more or all of the 20 pouches, while atmospheric pressure will be present in those pouches, if any, which do not contain regulated pressure. Whenever regulated pressure (which is always less than atmospheric pressure) is present in one or 25 more of the pouches 34, 35 and 36, the effect thereof is to produce a downward pull upon the board 33 (i. e. the differential between atmospheric pressure on the top of the board 33 and the lesser regulated pressure in one or more of the pouches); and this resultant downward pull opposes the upward pull by the pouch 37, the two contributing to control the valve 31. High exhaust in the 35 chest 14 exerts some downward pressure upon the area of the valve 31 itself; and the regulated pressure in the chest 12 exerts some upward pressure upon the area of the valve. The regulated pressure being greater, it predominates and the resultant upon the 40 valve itself is an upward pressure which combines with the resultant of the pressures in the several pouches to complete the control of the valve 31.

Thus the valve 31 is controlled by the differential between the upwardly acting pull of the pouch 37 and the pressure in the chest 12 on the valve itself, and the downwardly acting pulls of such of the pouches 34, 35, 36, as contain regulated pressure plus the 50 downward pressure of highly exhausted air in the chest 14 on the top of the valve 31. The areas of the various pouches, and their leverages in respect to the board 33, are such that these opposed upwardly and downwardly acting pressures so control the valve 31 as to tend to hold it in a balanced condition. For example, if regulated pressure be present in all three of the pouches 34, 35 and 36, the downward pull of these pouches 60 upon the board 33 is at its maximum and tends to close the valve 31 and minimize the opening between the chests 12 and 14. Such closing of the valve 31 and restriction of communication between the chests, tends to

reduce the suction in the regulated pressure 65 chest 12, and this reduction in suction is immediately communicated to the pouches 34, 35, and 36, to reduce the downward pull thereby. In this manner the tendency to close the valve 31 is checked and it is closed 70 to such an extent only as will produce a balance between the aforesaid downwardly acting forces and the upwardly acting forces.

If, under these circumstances, atmosphere be admitted, for instance, to the pouch 36, 75 the aggregate downward pull upon the board 33 is relaxed to some extent tending to permit the upwardly acting forces to open the valve 31 correspondingly. If the valve be thus opened, the communication between the 80 chests 12 and 14 is thereby enlarged so that the degree of exhaust of the regulated pressure is increased and thereby the downward pull by the pouches 34 and 35 is correspondingly increased until the downwardly and 85 upwardly acting forces are again brought to a balance.

If atmosphere be admitted to all the pouches 34, 35 and 36 the downward pull by 90 said pouches upon the board 33 will be minimized and the upwardly acting forces referred to will so largely predominate that the valve 31 will be open to enlarge communication between the chests 12 and 14 to the maximum.

It will be evident to those skilled in the art, that the more of the pouches 34, 35 and 36 which contain regulated pressure, the greater will be the aggregate downward pull by said pouches and the greater will be the 100 tendency to constrict communication between the chests 12 and 14 by the valve 31. In other words, the more of the pouches 34, 35 and 36 which contain regulated pressure, the less is regulated pressure subjected to 105 the influence of high exhaust and the less will be the intensity of sounded tones. Accordingly, the general operation of the pouches described may be conveniently summarized thus:—admitting regulated pressure to one or more pouches diminishes intensity; admitting atmospheric pressure to one or more pouches increases intensity.

In the operation of the specific illustrative apparatus the board 33 and valve 31 are constantly under the control of opposed forces tending always to balance each other and hold the valve 31, as it were, in suspension between them; that is to say, the specific apparatus tends constantly to establish a 115 balancing equation between the opposed forces acting upon the valve 31. Such movement of the valve 31 as may occur when that balancing equation is disturbed, takes place practically instantaneously so that a 120 new balancing equation appropriate to the newly initiated conditions is immediately set up.

The actual variation of regulated pressure may result from a number of causes, or a combination of causes, such that the valve 31 may or may not be moved to assist in a reestablishment of the pressure equation above referred to, which holds the valve in balance.

Normally, and even at a time when it is desired to maintain constant regulated pressure, some leakage of atmosphere to the chest 12, and various parts communicating therewith, may tend to reduce the degree of exhaust in said chest, whether or not any of the motor pneumatics F is in action. A reduction in regulated exhaust from such cause may be compensated to some extent by leakage between the high exhaust chest 14 and the chest 12, as by leakage past the valve 31. If, however, regulated pressure increase enough to disturb a prevailing pressure equation, there may result an upward movement of the valve 31 enlarging the opening between the chests 12 and 14 enough to permit high exhaust to restore the intended regulated exhaust in chest 12. Such action takes place so promptly and quickly, that, in effect, it serves to maintain regulated exhaust substantially constant (until intentionally varied), rather than to restore it.

Each motor pneumatic F, when idle, contains atmospheric which, when the pneumatic is thrown into operation, tends to increase regulated pressure in the chest 12. Obviously, if several motor pneumatics F act simultaneously there may be a considerable increase of regulated pressure. Ordinarily in the operation of the illustrative apparatus, the regulated pressure may be thus subjected to frequent fluctuations by the action of the motor pneumatics. Whenever such fluctuation so increases regulated pressure that a pressure equation is disturbed, the valve 31 may be moved to restore the equation as described. As already suggested, this restoring action takes place so quickly that it is rather a maintaining action in its general effect upon the regulated pressure.

From the above it appears that whatever draughts are made upon the regulated pressure chest 12, and from whatever cause, said pressure may be maintained always by the described balancing operation of the forces controlling communication between the chests 12 and 14 by the valve 31. Immediately, however, a deliberate, intentional change is made in the pneumatic conditions in the pouches 34, 35 and 36, or any thereof, the pressure equation is temporarily disturbed, to be restored when a new and different regulated pressure is established.

It will be noted that the regulating action of the described apparatus may serve merely to maintain the desired regulated pressure

in spite of any draughts made thereupon, as for instance, by the motor pneumatics. That is to say, the regulation does not necessarily result from varying communication between the high exhaust chest and the regulated pressure chest. For instance, assume that the selection of pouches 34, 35 and 36 containing regulated pressure be so changed that a considerable increase in regulated pressure is demanded to re-establish the pressure equation. Assume further that such change be accompanied by the action of a considerable number of motor pneumatics F, which in effect alone suffices to increase the regulated pressure so as to re-establish the balancing equation. Under such circumstances regulated pressure may be changed from a lower to a higher working level without making necessary any substantial change in the communication between the two chests 12 and 14. Thus in greater or less degree, the mere utilization of regulated pressure in the chest 12, may cooperate with the deliberate variations of pneumatic conditions in the pouches 34, 35 and 36, so that the control of communication between the chests by the valve 31 may be, and frequently it will be, of merely supplemental and auxiliary effect.

Hereinbefore a preferred form of regulating mechanism has been described. The manner in which the same may be governed to initiate different substantially distinct grades of regulated tension, will be next explained.

Referring again to the drawing, the duct 40 connects the pouch 34 with a valve chamber 49. In said chamber is a duplex valve 50, arranged for opening an upper port to atmosphere and alternatively opening a port from the chamber 49 through a duct 51 to the regulated tension chest 12. The valve 50 is controlled by a diaphragm of the chamber 54 which communicates with the duct 53. A duplex valve 58 controls a port from the duct 56 to atmosphere, and a second port from the duct 56 to a chamber 59 communicating by a duct 60 with the high exhaust chest 14. The valve 58 is controlled by a diaphragm of a chamber 62 which communicates by a duct 63 with the tracker vent T.

When the tracker vent T is open the diaphragm of chamber 62 and the valve 58 are elevated so as to vent the diaphragm chamber 54 to atmosphere and lift its diaphragm and the valve 50 and vent the duct 40 to atmosphere. The converse of this operation which closes the duct 40 to atmosphere and opens it to regulated tension, will be described hereinafter.

The parts just described are triplicated for controlling the ducts 41 and 42, the corresponding parts of the valve mechanism for the latter being indicated by the numerals 50, 51, etc., with indices "a"

for the valve mechanism for duct 41, and "b" for the valve mechanism for duct 42.

In the valve mechanism for duct 41 it is assumed that the duct 63^a to the tracker vent T^a is open to atmosphere; this lifts the diaphragm of chamber 62^a, venting chamber 54^a to atmosphere and admitting atmosphere to the duct 41, past the valve 50^a and to the pouch 35. Thus, whenever a tracker vent 10 T^a, T^a or T^b, is open, atmosphere is admitted to the corresponding pouch 34, 35 or 36.

When one of the valves 50, 50^a, 50^b is once opened by venting the corresponding 15 tracker duct, the valve preferably continues open even though the tracker vent may be immediately closed. In the specific apparatus this results from the fact that once the valve 58^a, for instance, is opened to admit atmosphere to the diaphragm chamber 54^a, said valve 58^a is held in that position by atmosphere admitted past the valve 58^a into a duct 70^a through a bleeder vent 72^a, and a duct 74^a (shown in dotted lines), 20 which latter communicates with the diaphragm chamber 62^a. The chamber 59^a above the diaphragm communicates as described with the high exhaust chest 14. Thus so long as atmosphere is admitted 25 through duct 70^a to duct 74^a the diaphragm of chamber 62^a will remain lifted and atmosphere will continue in the corresponding pouch 35. The parts just described as pertaining to the valve 50^a are triplicated to 30 cooperate with the valves 50 and 50^b.

From the preceding discussion it will appear that small perforations in a music sheet may be employed to open the tracker vents T, T^a and T^b which may be immediately closed if desired. When used with the 40 illustrative apparatus, each such perforation has the effect of introducing atmosphere to a pouch 34, 35 or 36 and even after the tracker vent is closed, atmosphere will 45 continue in the corresponding pouch until purposely exhausted at any desired subsequent time in a manner such as that about to be described.

The specific apparatus shown in the drawings comprises a single valve mechanism, controlled by a single tracker vent, which may cooperate with all or any of the three above described valve mechanisms, to negative the effect of opening one or more of 55 the tracker vents T, T^a and T^b. This single valve mechanism is shown at the right of Fig. 1.

A tracker vent R communicates by its duct 80 with a diaphragm chamber 82. The 60 latter controls a duplex valve 84 which in its alternative positions admits atmosphere to a duct 86 or opens communication between said duct 86 and a duct 88 leading to the high exhaust chest 14. An extension 65 of the duct 86 communicates with each of

the three diaphragm chambers 90, 90^a and 90^b. Thus, when atmosphere is admitted to the duct 86, past the valve 84, the diaphragms of the chambers 90, 90^a and 90^b are lifted. In describing the effect of this 70 operation, it is convenient to refer to chamber 90^a and associated parts.

As already stated, the valve 58^a is held in the open position shown, by the fact that atmosphere is present in the ducts 70^a and 74^a. When, however, the diaphragm of chamber 90^a is lifted, it lifts a disk valve 92^a and closes communication between duct 70^a and duct 74^a, thereby closing the latter from atmosphere. At the same time the valve 92^a 80 opens communication between the duct 74^a through the bleeder 72^a, with chamber 94^a which is open to high exhaust through the duct 60^a. In this manner the duct 74^a is connected with high exhaust which bleeds 85 the atmosphere from chamber 62^a thereby permitting valve 58^a to drop, shutting off atmosphere from the diaphragm chamber 54^a and throwing the latter into communication with the chamber 59^a and the high exhaust chest 14 through the duct 60^a. When 90 the diaphragm chamber 54^a is thus exhausted by high exhaust, the valve 50^a is permitted to drop shutting off atmosphere from the duct 41 and throwing the latter into communication with the duct 51^a leading to the regulated pressure chest 12. In this manner, by opening the tracker vent R, the duct 41 and its pouch 35 are closed to atmosphere 95 and opened to regulated pressure. 100

The operation just described, so far as concerns the specific illustrative mechanism depends upon bleeding the diaphragm chamber 62^a. If the tracker duct 63^a be open through its vent T^a, at the time the vent R 105 is opened to initiate the bleeding of diaphragm chambers 62^a, atmosphere will enter the chamber 62^a more rapidly than it can be exhausted therefrom by the described bleeding; therefore the effect of opening the vent 110 R is negated, and in such circumstances that valve 58^a will remain open and atmosphere will continue in the corresponding cylinder chamber.

Also, if the tracker vent T, for instance, 115 be open simultaneously with the tracker vent R, the latter will inaugurate a tendency to bleed the chamber 62 and keep the valve 58 closed in the position shown, but the simultaneous opening of the tracker vent T will 120 admit atmosphere to the chamber 62 more rapidly than it can be exhausted by bleeding and therefore the valve 58 will be lifted in spite of the opening of the tracker vent R.

From the above description it will be understood that whether or not the tracker vent R be open, the opening of any of the vents T, T^a, T^b will have its normal and usual effect to admit atmosphere to the appropriate pouch or pouches 34, 35 and 36. 130

This will be true if any vent T , T' , T'' , be opened with or without simultaneously opening the tracker vent R .

On the other hand, if the vent T' be opened and then closed (atmosphere being thereby admitted to the pouch 34) and the vent R be thereafter opened, the previous effect of opening vent T' will be negated and the pouch 34 opened to regulated pressure.

The effect of opening and closing the various tracker ducts in the specific mechanism may be readily understood by referring to an illustrative form of perforated music sheet diagrammed in Fig. 2 in which are shown four lines of perforations at the top for governing the above described expression controlling tracker vents. The music sheet may be assumed to be travelling in the direction of the arrow in Fig. 2. The tracker G is shown in dotted lines in Fig. 2 the vent T' being open through the perforation 100 in the sheet. All the other vents are closed. The perforations in the sheet for operating the motor pneumatics may be disregarded for brevity.

When the note sheet and tracker are related as shown in Fig. 2, the various valve mechanisms occupy exactly the positions shown in Fig. 1. If now the music sheet progresses in the direction of the arrow, perforation 301 will presently open the vent R ; this will lift the diaphragm of chamber 82; open the duct 86 to atmosphere; admit atmosphere to diaphragm chamber 90^a; lift valve 92^a; and throw the diaphragm chamber 62^a into communication with the high exhaust chest 14, through the duct 74^a, past the bleeder 72^a, through the chamber 94^a and duct 60^a. This permits the valve 58^a to drop and thereby the diaphragm chamber 54^a is exhausted as described, with the final result that the cylinder duct 41 and pouch 35 are closed to atmosphere and opened to regulated pressure. In these circumstances regulated pressure is present in all of the pouches 34, 35 and 36 and the playing is at the lowest intensity.

When the music sheet progresses further the perforation 302 opens the vent T and, as will be understood, thereby opens the duct 40 and pouch 34 to atmosphere. Thereafter a perforation 303 and a perforation 304 register respectively and simultaneously with the vents R and T' . The perforation 303 negates the previous effect of the perforation 302 and opens the pouch 34 to regulated pressure. The perforation 303 is ineffective, however, in respect to perforation 304 which opens the vent T' and thereby admits atmosphere to the pouch 35.

As the note sheet progresses further, perforations 305 and 306 open the vents T and T' which admit atmosphere to the pouches 34 and 36. The previous effect of the per-

foration 304 endures, and thereby, by reason of the three perforations 304, 305, and 306, atmosphere is present in all of the pouches 34, 35 and 36, and the playing is at highest intensity.

Next a perforation 307 opens the vent R and simultaneously a perforation 308 opens the vent T' . The effect of the perforation 307 is to negative the previous effect of both the perforations 305 and 306 and to open the pouches 34 and 36 to regulated pressure. The perforation 307, however, is ineffective in respect to perforation 308 which merely continues the previously established effect of the perforation 304 leaving the pouch 35 still open to atmosphere.

Next perforations 309 and 310 reinstate atmosphere in the pouches 34 and 36 and again all of the pouches 34, 35 and 36 are open to atmosphere.

Next a perforation 310 opens the vent R at a time when all the other vents are closed and thereby negatives the effects of all three perforations 308, 309 and 310 with the result that all the pouches 34, 35 and 36 are closed to atmosphere and open to regulated pressure to reduce the playing to lowest intensity.

The preceding description will suffice to indicate the variety of combinations of perforations whereby atmosphere and regulated pressure may be alternated in one or more of the pouches with the resultant variations in regulated pressure and in the intensities of notes played thereby.

As will appear to those skilled in the art the usual note perforations may occur in the music sheet or may be related with the described expression-regulating perforations in any practicable manner, as, for instance, by aligning or substantially aligning the advance end of a note perforation with one or more expression perforations to establish the regulated pressure in the chest 12 for playing the note with desired intensity.

The preceding description has been devoted to an illustrative form of apparatus by which substantially distinct grades or degrees of regulated exhaust may be established for playing notes with substantially distinct grades of intensity, each such grade being louder or softer than the next grade by a more or less definite and considerable increment. Such an apparatus may be employed to advantage in conjunction with a so-called "crescendo and diminuendo apparatus" next to be described; but the illustrative form of the latter shown in the drawings, is likewise susceptible of being used separately and it will be first explained as used independently of all the other apparatus except the illustrative valve 31 which exemplifies means for controlling and varying the regulated exhaust in producing crescendo and diminuendo effects.

In this connection it will be assumed for

the present that the pneumatic conditions in the respective pouches 34, 35 and 36, are maintained constant during operation of the crescendo and diminuendo apparatus, as by 5 having regulated exhaust present in all said pouches for playing with lowest intensity.

In the foregoing description it has been assumed that the degree of exhaust in the pouch 37 has been maintained constant, 10 though always less than atmospheric pressure, so as to produce in effect an upward pull upon the board 33. This upward pull by the pouch 37 being opposed as described by the pouches 34, 35 and 36, which exert a 15 variable aggregate downward pull, the resultant of these downward and upward pulls has been shown to be a variable by which the playing intensities may be varied by distinct increments to different levels, so to speak.

20 The degree of exhaust in the pouch 37 is also preferably variable, to afford an additional means for varying the resultant between the said upward and downward pulls and thereby further varying the control of 25 the valve 31 and the playing intensities.

The means by which a normal minimum degree of exhaust may be maintained in the pouch 37 will be first described. A duct 100 connects the interior of the pouch 37 with a valve chest 101 containing a needle valve 102. When the valve 102 is in the position shown in Fig. 1 it restricts communication between the duct 100 and a duct 103 which leads to a source of high exhaust. 30 Thus in effect with the valve 102 in the position shown there is a bleeding of air from the pouch 37 through the duct 100 and chamber 101 past the valve 102.

Another duct 104 connects the interior of 40 the pouch 37 with the interior of an equalizer pneumatic 105, which has a small bleeding vent 106 to atmosphere. The capacity of the bleed to exhaust past the valve 102, and the capacity of the vent 106 to atmosphere are so proportioned that a certain 45 minimum degree of exhaust is maintained, as will be understood by those skilled in the art, in the pouch 37. The equalizer pneumatic 105 having a spring 107 is employed 50 to provide a sufficient volume of air in elastic condition to render the pouch 37 sensitive and readily responsive to such movement of the board 33 as takes place in the operation of the valve 31.

55 The bleed to exhaust past the valve 102 being so related to the atmosphere bleed 106 as to maintain a certain minimum degree of exhaust in the pouch 37, it will be evident to those skilled in the art that if the relation 60 between these bleeds be changed (as by increasing the exhaust bleed, or diminishing the atmosphere bleed) so as to increase the degree of exhaust in the pouch 37, then the upward pull by the pouch may be increased 65 with a tendency to open the valve 31 to in-

crease the playing intensities. To illustrate means for thus changing the relation between said exhaust and atmosphere bleeds, the drawings show the needle valve 102 which, being moved upwardly, gradually increases the exhaust bleed (the atmosphere bleed 106 remaining for convenience constant) thereby gradually increasing the degree of exhaust in the pouch 37, gradually increasing the upward pull on the board 33 70 and valve 31, so as to produce an excellent crescendo effect. Obviously, the speed with which the needle valve 102 is moved may be made to determine the speed of the crescendo. 75

The upper end of the valve 102 is connected by a link 110 with the movable board 111 of a pneumatic 112, provided with a spring 113. A preferably adjustable stop 114 for the movable board 111 is provided, 80 to hold the movable board and valve 102 in position to maintain the desired minimum bleed to exhaust through the chamber 101 and past the valve 102 when the pneumatic 112 is in fully expanded position.

In the specific illustrative apparatus the pneumatic 112 is arranged to be collapsed at different speeds, so as to open the needle valve at different speeds and produce correspondingly fast or slow crescendos. 90

A duct 115 leads from the interior of the pneumatic 112 to an adjustable bleeder vent 116 and a second adjustable vent 117 and is connected by a tube 118 with a valve chamber 119 controlled by a valve 120 which admits to said chamber either atmosphere or high exhaust from a chest 121. Channels 122, 123 and a diaphragm 124 provide a free by-pass around the bleeder vent 116. The diaphragm 124 carries a valve block 125 for closing off the by-pass 122, 123 and the valve block 125 is controlled by a diaphragm 126 over a chamber 127 connected by a tube 128 with a valve chamber 129 controlled by a valve 130 which admits to said chamber either atmosphere or high exhaust from the chest 121. The valve 120 is controlled by a diaphragm 132, the chamber of which is connected by a duct 133 with a tracker vent 134. The valve 130 is controlled by a diaphragm 135, the chamber of which is connected by a duct 136 with a tracker vent 137. 100

In the operation of this specific apparatus the adjustable bleeder vent 116 is utilized to 120 determine the minimum speed of exhaustion of pneumatic 112 for slow crescendo purposes; and likewise the minimum speed at which atmosphere is re-admitted to the said pneumatic for slow diminuendo purposes. The bleeder vent 117 is adjusted to provide a less constriction of the passage 115 than that determined by the adjustable vent 116; and said vent 117 is used to determine the greater speed of exhaust of the pneumatic 112 130

for fast crescendo purposes, and likewise the greater speed of re-admission of atmosphere to the pneumatic for fast decrescendo purposes.

5 When it is desired to produce a slow crescendo, the tracker vent 134 is opened by a perforation in the music sheet; the valve 120 is thereby lifted to admit suction from the chest 121 into the tube 118; and thus suction exhausts from the pneumatic 112 through the duct 115 and past the restriction of the bleeder vent 116. During this time the valve 130 standing in the position shown, permits the presence of atmosphere in the tube 128 and diaphragm chamber 127 and thereby holds the valve block 125 in position to close the by-pass 122, 123. A spring 140 may be located in the diaphragm chamber 127 to assist in holding the valve 125 closed.

10 to shut off the by-pass. Thus, for the slow crescendo the exhaust of the pneumatic 112 is retarded by the vent 116 and therefore the pneumatic 112 is gradually collapsed at whatever slow speed may be determined by 15 the adjustment of the vent 116. This gradual collapse of the pneumatic 112 moves the needle valve 102 upwardly and gradually increases the opening between the exhaust duct 103 and the duct 100 leading to the 20 pouch 37. This, as already described, gradually increases the upward pull exerted by the pouch 37 and causes a slow crescendo.

To produce a slow decrescendo, the valve 134 in the tracker is closed (by terminating 25 a perforation in the music sheet) and thereby the valve 120 is permitted to resume the position shown in the drawing. This re-admits atmosphere to the tube 116 and the same bleeds back into the pneumatic 112 past 30 the restriction by the adjustable vent 116, such restriction retarding the expansion of the pneumatic 112 and causing the needle valve 102 gradually to diminish the opening between the exhaust duct 103 and the duct 40 leading to the pneumatic 37. This gradually reduces the upward pull which, at 45 the end of the crescendo was being exerted by the pouch 37, and thereby causes a slow decrescendo.

50 In the slow crescendo and decrescendo operations, the adjustable bleeder vent 117 performs no essential office since the greater restriction of the passage 115 by the vent 116 controls the speed of exhaustion and refilling 55 of the pneumatic 112.

When, however, it is desired to produce a fast crescendo the tracker vent 137 is opened (as by a perforation in the music sheet); the valve 130 is thereby lifted; exhaust from 60 the chest 121 is admitted to the tube 128 and therethrough to the diaphragm chamber 127, whereby the diaphragm 126 is permitted to be pressed downwardly by exterior atmospheric pressure and thus the valve 125 is lowered to open the by-pass 122, 123. If the 65 tracker vent 134 be also opened, or contam- 70 ously with the vent 137, exhaust is also admitted through the tube 118 to the interior of the pneumatic 112; but in this case instead of being obliged to pass the greater 75 restriction by the vent 116, the suction is subject only to the less restriction by the vent 117 and is permitted to by-pass the vent 116 through the channels 122, 123, and the diaphragm 124. The exhaust is therefore 80 permitted two paths, one past the vent 116 and the other through the by-pass 122, 123; but the speed of exhaustion under these circumstances is determined by the adjustment of the vent 117 and that adjustment is made so to suit the desired speed for a fast crescendo which ensues similarly to the slow crescendo but at a greater speed, as will be understood by those skilled in the art.

When a fast decrescendo is desired, the vent 137 is left open (as by continuing the perforation in the music sheet) and the vent 134 is closed. Thus the valve 130 is held in elevated position to continue the open condition of the by-pass 122, 123, while the valve 120 is dropped to the position shown in the drawing to admit atmosphere to the tube 116, past the vent 117 and through the double path of the by-pass 122, 123 and the vent 116. In this way the speed of the decrescendo is likewise determined by the adjustment of the vent 117 and the decrescendo ensues as in the case of the slow decrescendo already described, but at a high speed.

It will be evident to those skilled in the art, that the crescendo vent 134 may be opened by a succession of small perforations in the music sheet so as to produce a succession of steps of collapsing movement of the pneumatic 112 thereby producing a crescendo in steps, the speed of this succession of steps being determined by the spaces between the perforations in the series; or the crescendo vent 134 may be opened by a continuous perforation, or a series of small perforations having the effect of a continuous perforation, with the result that the collapse of the pneumatic 112 will be continuously progressive to produce a smooth and unbroken crescendo.

Similarly, a decrescendo may be produced in steps or a continuous progression by suitably disposing the controlling perforations in the music sheet.

The regulation of playing intensity in substantially distinct steps as already described, and the creation of crescendo and decrescendo effects, may be combined with great advantage. For example, the valve mechanisms controlled by the vents T, T', T" and R may determine the starting point in the scale of intensities, of a crescendo or diminuendo whereby a crescendo or a diminuendo may be superposed, as it were, upon an already existing intensity regulation deter-

mined by the previous opening of one or more of the events T, T^a, T^b and R.

Either the slow crescendo produced by opening the vent 134 alone, or the rapid crescendo produced by causing both vents 134 and 137 to be opened, may be superposed upon an already existing intensity regulation. In the same manner the rapid crescendo may be superposed upon a slow crescendo by first opening the vent 134 and thereafter opening the vent 137; or both said vents being open the slow crescendo may be superposed upon the rapid crescendo by causing the vent 137 to be closed, the vent 134 remaining open.

Similarly, a fast diminuendo may be superposed upon an already existing slower diminuendo, or vice versa. Furthermore, as will appear to those skilled in the art, the playing intensity may be increased by a sudden practically instantaneous step superposed upon a crescendo which is in progress, thereby, for example, particularly emphasizing some note or notes in the crescendo. Such effects, and many others, may be produced by appropriately combining the crescendo and diminuendo effects with each other and with the increasing and decreasing of intensities by the distinct steps; it is, however, deemed unnecessary to describe these various combined effects in any greater detail since they will be readily understood by those skilled in the art.

In Fig. 2 the arrangement of a perforated music sheet for producing some of these combined effects, is shown for illustration. For instance, a perforation 315 is provided for opening the tracker duct 134 to produce a slow crescendo, followed, when the vent 134 is again closed, by a slow decrescendo. As already described, the perforation 311 in the music sheet has had the effect of introducing regulated pressure to all of the pouches 34, 35 and 36, and therefore the slow crescendo caused by the perforation 315 starts at the lowest level of playing intensity and crescendoes from that level so long as the perforation 315 continues, and then decrescendoes to the lowest level of intensity. Thereafter, a perforation 316 opens the tracker vent T, thereby admitting atmosphere to the pouch 34 and causing the instrument to play louder by a distinct step. When, therefore, the perforations 317 and 318 start a fast crescendo, the latter begins at a louder level of playing and crescendoes from that. It will be noted that the perforation 318 controlling the speed of operation of the pneumatic 112, extends beyond the rear end of the perforation 317 so that the combined effects of the perforations 317 and 318 produce a fast crescendo so long as the former acts, following by a fast decrescendo. Thereafter, a perforation 319 starts a slow crescendo during which it may be assumed for illustration, it

is desired to emphasize some note or notes by introducing an increase in playing intensity by a distinct step, and immediately thereafter eliminating this increase to permit the crescendo to continue without further emphasis.

While the slow crescendo caused by the perforation 319 is in progress, two perforations 320 and 321 introduce atmosphere to the pouches 35 and 36 and this combining with the effect of the perforation 316 causes the loudest playing to ensue. Shortly thereafter, however, the perforation 322 negatives the effect of the perforations 320 and 321 while the perforation 323 continues the previous effect of the perforation 316 so that the level of intensity upon which the crescendo started is restored, and the crescendo continues so long as perforation 318 holds the vent 134 open. As will appear to those skilled in the art, the effect of the perforations 320 and 321, followed more or less promptly by the perforations 322 and 323, is to select a certain stage in the crescendo at which notes will be particularly emphasized above the intensities which they would otherwise have in the crescendo at that time.

For further illustration, a perforation 324 starts a fast crescendo during the progress of the slow crescendo by the perforation 319, and after the latter perforation has terminated, the prolongation of the perforation 324 causes a fast crescendo. If the perforation 324 be terminated before the pneumatic 112 has had time to expand to the fully open position, then the remaining expansion, after the perforation 324 has passed the tracker, results in a slow crescendo to the level of intensity determined by the perforation 323.

The foregoing will suffice to illustrate the various combined arrangements of intensity-step controlling perforations, and crescendo and diminuendo perforations, by which a great variety of effects may be produced as will appear to those skilled in the art.

It is to be understood that the invention is not limited to the specific details of construction, organization and mode of operation hereinbefore described for purposes of illustration. On the contrary, the invention may be variously modified within the scope of the subjoined claims as will appear to those skilled in the art.

Claims:

1. An instrument of the character described comprising, in combination, pneumatic playing actions, a main source of pneumatic power for operating said playing actions; and, regulating means interposed between said main source of power and said pneumatic actions, for maintaining uniformity of playing intensities, whether one or many tones be sounded, said regulating means comprising a valve, a pneumatic to

receive regulated pressure, and an oppositely acting pneumatic partially exhausted, said pneumatics conjointly controlling said valve; and means to vary the degree of exhaust in 5 said partially exhausted pneumatic to vary the regulation and produce different playing intensities.

2. An instrument of the character described comprising, in combination, pneumatic playing actions, a main source of 10 pneumatic power for operating said playing actions; a regulating valve interposed between said main source of power and said pneumatic actions; a regulating pneumatic 15 connected to said valve; means for connecting said regulating pneumatic to regulated pressure; a pneumatic acting upon said valve in opposition to said regulating pneumatic and normally maintained partially exhausted; and means to vary the degree of 20 exhaust within said pneumatic from the normal.

3. An instrument of the character described comprising, in combination, pneumatic playing actions, a main source of 25 pneumatic power for operating said playing actions; a regulating valve interposed between said main source of power and said pneumatic actions; a regulating pneumatic 30 connected to said valve; means for connecting said regulating pneumatic to regulated pressure; pneumatic means connected to said valve to exert a continuous pull relative thereto in opposition to said regulating 35 pneumatic; and means to vary the force of said pull by substantially continuous progression.

4. An instrument of the character described comprising, in combination, pneumatic playing actions, a main source of 40 pneumatic power for operating said playing actions; a regulating valve interposed between said main source of power and said pneumatic actions; a regulating pneumatic connected to said valve; means for connecting 45 said regulating pneumatic to regulated pressure; pneumatic means connected to said valve; controlling means for said pneumatic means to normally maintain a constant pull 50 thereby in opposition to said regulating pneumatic; and means to vary by substantially continuous progression the pull by said pneumatic means for correspondingly 55 varying the regulation and the playing intensities.

5. An instrument of the character described comprising, in combination, pneumatic playing actions, a main source of pneumatic power for operating said playing 60 actions; regulating means interposed between said main source of power and said pneumatic actions, and comprising opposed pneumatic means one of them arranged to receive regulated pressure and the other arranged to be variably exhausted; and means 65

for varying the degree of exhaust at said last named pneumatic means.

6. An instrument of the character described comprising, in combination, pneumatic playing actions, a main source of 70 pneumatic power for operating said playing actions; regulating means interposed between said main source of power and said pneumatic actions, and comprising opposed pneumatic means one of them arranged to 75 receive regulated pressure and the other arranged to be variably exhausted; means for varying the degree of exhaust at said last named pneumatic means; and means to vary the speed of exhaustion of said last named 80 pneumatic means.

7. An instrument of the character described comprising, in combination, pneumatic playing actions, a main source of pneumatic power for operating said playing 85 actions; a regulating valve interposed between the main source of power and the regulating pneumatic actions; pneumatic means for opening said valve; a valve for governing the exhaust of said pneumatic 90 means to open the regulating valve; and automatic means to control said valve.

8. An instrument of the character described comprising, in combination, pneumatic playing actions, a main source of 95 pneumatic power for operating said playing actions; a regulating valve interposed between the main source of power and said pneumatic actions; pneumatic means for opening the regulating valve; a valve for 100 governing the exhausting of said pneumatic means to open the regulating valve; and automatic variable-speed means for controlling said valve.

9. An instrument of the character described comprising, in combination, pneumatic playing actions, a main source of pneumatic power for operating said playing 105 actions; a regulating valve interposed between the main source of power and said pneumatic actions; pneumatic means for opening the regulating valve; a valve for governing the exhausting of said pneumatic 110 means to open the regulating valve; a tracker; means connected to the tracker for 115 operating said valve, and other means connected with the tracker for varying the speed of operation of said valve.

10. An instrument of the character described comprising, in combination, pneumatic playing actions, a main source of pneumatic power for operating said playing actions; a throttle valve interposed between the main source of power and said pneumatic actions; a movable member connected 120 to said valve for governing its throttling action; pneumatic means adapted to receive regulated pressure, connected to said movable member and tending to move the same in one direction; and pneumatic means con- 125 130

- nected to said movable member and tending to move it in opposition to said first named means; and means to vary the degree of exhaust in said second pneumatic means for producing crescendo and diminuendo effects.
11. An instrument of the character described comprising, in combination, pneumatic playing actions, a main source of pneumatic power for operating said playing actions; a throttle valve interposed between said main source of power and said pneumatic actions; a movable member connected to said valve for governing its throttling action; pneumatic expression governing means for varying expression by distinct increments, acting upon said movable member and tending to move the same in one direction; and pneumatic crescendo means acting upon said movable member and tending to move it in opposition to said expression means.
12. An instrument of the character described comprising, in combination, pneumatic playing actions, a main source of pneumatic power for operating said playing actions; a regulator interposed between said main source of power and said pneumatic actions, said regulator comprising opposed pneumatic means; automatic means for varying the acting area of one of said pneumatic means to vary playing intensities by distinct increments; and means to vary the degree of exhaust in the opposing pneumatic means to produce crescendo effects.
13. An instrument of the character described comprising, in combination, pneumatic playing actions, a main source of pneumatic power for operating said playing actions; a valve interposed between said main source of power and said pneumatic actions; and governing means for said valve comprising pneumatic means having a vent to atmosphere and a vent to suction, said vents having their capacities related to maintain suction in said pneumatic.
14. An instrument of the character described comprising, in combination, pneumatic playing actions, a main source of pneumatic power for operating said playing actions; a valve interposed between said main source of power and said pneumatic actions; governing means for said valve comprising pneumatic means having a bleed to atmosphere and a bleed to suction, the capacities of said bleeds being so related as to maintain suction in said pneumatic means; and means to vary the relative capacities of said bleeds to vary the degree of suction in said pneumatic means.
15. An instrument of the character described comprising, in combination, pneumatic playing actions, a main source of pneumatic power for operating said playing actions; a valve interposed between said main source of power and said pneumatic
- actions; and governing means for said valve comprising pneumatic means having a bleed to atmosphere and a bleed to suction; a tracker; and means connected to the tracker for varying the relative capacities of said bleeds.
16. An instrument of the character described comprising, in combination, pneumatic playing actions, a main source of pneumatic power for operating said playing actions; a valve interposed between said main source of power and said pneumatic actions; and governing means for said valve comprising pneumatic means having a bleed to atmosphere and a bleed to suction, a valve for varying the relative capacities of said bleeds, and automatic means for operating said valve.
17. An instrument of the character described comprising, in combination, pneumatic playing actions, a main source of pneumatic power for operating said playing actions; a valve interposed between said main source of power and said pneumatic actions; and governing means for said valve comprising pneumatic means having a bleed to atmosphere and a bleed to suction, a valve for varying the relative capacities of said bleeds, automatic means for operating said valve, and means for varying the speed of operation of said valve.
18. An instrument of the character described comprising, in combination, pneumatic playing actions, a main source of pneumatic power for operating said playing actions; a valve interposed between said main source of power and said pneumatic actions; and automatic crescendo means comprising pneumatic means having bleeds to atmosphere and exhaust, connections from said pneumatic means to the valve, and means for gradually varying the relative capacities of said bleeds to vary gradually the operation of said pneumatic means.
19. An instrument of the character described comprising, in combination, pneumatic playing actions, a main source of pneumatic power for operating said playing actions; a valve interposed between said main source of power and said pneumatic actions; governing means for said valve comprising pneumatic means having bleeds to atmosphere and exhaust; means for relatively varying the capacities of said bleeds; a pneumatic for operating said last-named means; and means for operating said pneumatic at different speeds.
20. An instrument of the character described comprising, in combination, pneumatic playing actions, a main source of pneumatic power for operating said playing actions; a valve interposed between said main source of power and said pneumatic actions; and governing means for said valve comprising pneumatic means having bleeds

- to atmosphere and suction, a needle valve for varying the capacity of one of said bleeds, a tracker, and means connected to the tracker for governing said needle valve.
- 5 21. An instrument of the character described comprising, in combination, pneumatic playing actions, a main source of pneumatic power for operating said playing actions; a valve interposed between said main
- 10 source of power and said pneumatic actions; and governing means for said valve comprising pneumatic means having bleeds to atmosphere and suction, a needle valve for varying the capacity of one of said bleeds, a tracker,
- 15 and means connected to the tracker for operating said needle valve at different speeds.
22. An instrument of the character described comprising, in combination, pneumatic playing actions, a main source of pneumatic power for operating said playing actions, a valve interposed between said main source of power and said pneumatic actions; and governing means for said valve comprising a plurality of pouches each operatively
- 25 connected to said valve, means to admit regulated pressure to said pouches to regulate said valve and maintain playing intensities whether one or many tones be sounded, and selective means to determine which of said
- 30 pouches shall receive regulated pressure.
23. An instrument of the character described comprising, in combination, pneumatic playing actions, a main source of pneumatic power for operating said playing actions; a valve interposed between said main source of power and said pneumatic actions; and governing means for said valve comprising a lever operatively connected to said valve, pneumatic means acting upon
- 35 said lever, and means for varying the leverage of said pneumatic means on said lever.
24. An instrument of the character described comprising, in combination, pneumatic playing actions, a main source of pneumatic power for operating said playing actions; a valve interposed between said main source of power and said pneumatic actions; and governing means for said valve comprising a lever operatively connected to
- 40 said valve, pneumatic means operable upon said lever with different leverages, and means to vary the acting area of said pneumatic means.
25. An instrument of the character described comprising, in combination, pneumatic playing actions, a main source of pneumatic power for operating said playing actions; a valve interposed between said main source of power and said pneumatic actions; and governing means for said valve comprising a lever, a plurality of pneumatic means operatively connected to said lever to act thereupon at different distances from its fulcrum, and means for operating said
- 45 pneumatic means selectively.
26. An instrument of the character described comprising, in combination, pneumatic playing actions, a main source of pneumatic power for operating said playing actions, and a plurality of cumulatively operable regulating pneumatics operatively connected to a valve interposed between the main source of power and said playing pneumatic to maintain playing intensities whether one or many tones be sounded, comprising a plurality of cumulatively operable pneumatics, pneumatic means opposing the operation of said pneumatics, and means for throwing said regulating pneumatics respectively into and out of operation, and pneumatic means opposing the operation of said regulating pneumatics.
27. An instrument of the character described comprising, in combination, pneumatic playing actions, a main source of pneumatic power for operating said playing actions; a plurality of cumulatively operable regulating pneumatics operatively connected to a valve interposed between the main source of power and said playing pneumatics to maintain playing intensities whether one or many tones be sounded; a common lever to which said regulating pneumatics are connected at different distances from the fulcrum; means opposing the operation of said pneumatics upon said lever; and means for throwing said pneumatics respectively into and out of operation.
28. An instrument of the character described comprising, in combination, pneumatic playing actions; a main source of power for operating said playing actions; a throttle valve interposed between said main source of power and the playing actions; and a plurality of independently operable regulating pneumatics connected to said throttle valve adapted each to establish a different degree of regulation in the power applied to said playing actions.
29. An instrument of the character described comprising, in combination, pneumatic playing actions; a main source of power for operating said playing actions; a throttle valve interposed between said main source of power and the playing actions; and a plurality of independently operable regulating means connected to said throttle valve; means to introduce regulated exhaust to said regulating means selectively or in combination, whereby with the introduction of regulated exhaust to each such means successively the playing intensities will be decreased.
30. An instrument of the character described comprising, in combination, pneumatic playing actions; a main source of power for operating said playing actions; a throttle valve interposed between said main source of power and the playing actions; a plurality of regulating means operatively

connected to said throttle valve for varying the degree of power applied to said playing actions; means to connect said plurality of regulating means selectively or in combination to a source of exhaust controlled by said throttle valve for regulating the degree of power applied to the playing actions at different predetermined levels.

31. An instrument of the character described comprising, in combination, pneumatic playing actions, a main source of pneumatic power for operating said playing actions; regulating means interposed between said main source of power and said pneumatic actions, for maintaining uniformity of playing intensities, whether one or many tones be sounded, said regulating means comprising a valve, a pneumatic to receive regulated pressure, and an oppositely acting pneumatic partially exhausted, said pneumatics conjointly controlling said valve, and means to vary by substantially continuous progression the degree of exhaust in said partially exhausted pneumatic thereby to produce substantially continuous progressive changes in playing intensities.

32. An instrument of the character described comprising, in combination, pneumatic playing actions, a main source of pneumatic power for operating said playing actions; regulating means interposed between said main source of power and said pneumatic actions, for maintaining uniformity of playing intensities, whether one or many tones be sounded, said regulating means comprising a valve, a pneumatic to receive regulated pressure, and an oppositely acting pneumatic partially exhausted, said pneumatics conjointly controlling said valve; and means to increase by substantially continuous progression the degree of exhaust in said partially exhausted pneumatic to produce crescendo changes in playing intensities.

33. An instrument of the character described comprising, in combination, pneumatic playing actions, a main source of pneumatic power for operating said playing actions; regulating means interposed between said main source of power and said pneumatic actions, for maintaining uniformity of playing intensities, whether one or many tones be sounded, said regulating means comprising a valve, a pneumatic to receive regulated pressure, and an oppositely acting pneumatic partially exhausted, said pneumatics conjointly controlling said valve; and means to decrease by substantially continuous progression the degree of exhaust in said partially exhausted pneumatic to produce diminuendo changes in playing intensities.

34. An instrument of the character described comprising, in combination, pneumatic playing actions, a main source of

pneumatic power for operating said playing actions; a valve interposed between said main source of power and said pneumatic actions; governing means for said valve including a lever and a plurality of pneumatic means operatively connected to said lever to act thereupon at different distances from its fulcrum; and means for adjusting the acting points of said pneumatic means on said lever relatively to the fulcrum.

35. An instrument of the character described comprising, in combination, pneumatic playing actions, a main source of pneumatic power for operating said playing actions; a valve interposed between said main source of power and said pneumatic actions; governing means for said valve including a lever and a plurality of pneumatic means operatively connected to said lever to act thereupon at different distances from its fulcrum; means for adjusting the acting points of said pneumatic means on said lever relatively to the fulcrum; and means for operating said pneumatic means selectively.

36. An instrument of the character described comprising, in combination, pneumatic playing actions; a main source of pneumatic power for operating said playing actions; and regulating means interposed between the main source of power and said playing pneumatics to maintain playing intensities whether one or many tones be sounded, said regulating means comprising a lever, pneumatic means progressively acting upon said lever between the fulcrum and the end thereof, and means opposing the operation of said pneumatic means.

37. An instrument of the character described comprising, in combination, pneumatic playing actions; a main source of pneumatic power for operating said playing actions; and regulating means interposed between the main source of power and said playing pneumatics to maintain playing intensities whether one or many tones be sounded, said regulating means comprising a lever, pneumatic means progressively acting upon said lever between the fulcrum and the end thereof, means to control the action of said progressively acting pneumatic means upon said lever, and means opposing the operation of said pneumatic means.

38. An instrument of the character described comprising, in combination, playing pneumatics; a main source of power for operating said player pneumatics; a valve interposed between the main source of power and said playing pneumatics; means operatively connected to and tending to close said valve; means operatively connected to and tending to open said valve, including an air container having a movable wall operatively connected to said valve; and

means to vary the degree of exhaust in said container to vary playing intensities while maintaining communication between all parts of said air container.

5 39. An instrument of the character described comprising, in combination, playing pneumatics; a main source of power for operating said player pneumatics; a valve interposed between the main source of power 10 and said playing pneumatics; means operatively connected to and tending to close said valve; means operatively connected to and tending to open said valve, including an air container having a movable wall operatively connected to said valve, adapted to contain a body of air under tension, and means to vary the tension of said contained 15 air to vary playing intensities while maintaining communication between all parts of 20 said air container.

40. In a musical instrument, the combination of playing pneumatics; a main source of power for operating the playing pneumatics; regulating means for regulating the 25 flow of air between the playing pneumatics and said source of power comprising means providing a lever acted upon by opposed forces; and means for varying the point of 30 application upon said lever of at least one of said opposed forces relatively to the fulcrum.

41. In a musical instrument, the combination of playing pneumatics; a main source of power for operating the playing pneumatics; regulating means for regulating the 35 flow of air between the playing pneumatics and said source of power comprising means

providing a lever acted upon by opposed forces; and pneumatically operable means for varying the leverage of at least one of 40 said opposed forces.

42. In a musical instrument, the combination of playing pneumatics; a source of power for operating the playing pneumatics; a valve between said source of power and 45 playing pneumatics; a regulator having operative connection with said valve; pneumatic means for tensioning said regulator; a valve and valve casing for controlling said pneumatic tension means; expression bellows to cause relative movement between the valve and valve casing to vary the pull of 50 said pneumatic tension means upon the regulator.

43. In a musical instrument, the combination of playing pneumatics; a source of power for operating the playing pneumatics; a valve between said source of power and the playing pneumatics; a regulator having operative connection with said valve; pneumatic means for tensioning said regulator; a valve and valve casing for controlling 55 said pneumatic tension means; expression bellows to cause relative movement between the valve and valve casing to vary rapidly 60 or gradually the pull of said pneumatic tension means upon the regulator.

In testimony whereof, I have signed my name to this specification, in the presence of two subscribing witnesses.

CHARLES F. STODDARD.

Witnesses:

LAURENCE A. JANNWAY,
EDW. A. JOHNSON.

Certificate of Correction.

It is hereby certified that in Letters Patent No. 1,409,482, granted March 14, 1922, upon the application of Charles F. Stoddard, of New York, N. Y., for an improvement in "Automatic Musical Instruments," errors appear in the printed specification requiring correction as follows: Page 3, line 113, for the misspelled word "diphramg" read *diaphragm*; page 7, line 116, for "descrescendo" read *decrecendo*; page 9, line 15, claim 2, for "connected" read *connected*; same page, lines 87 and 88, claim 7, strike out the words "the regulating" and insert instead the word *said*, and line 89, for the word "said" read *the regulating*; page 10, line 4, claim 10, for the word "exhause" read *exhaust*; page 11, line 73, claim 26, for the word "pneumatic" read *pneumatics*; same page and claim, line 75, commencing with the word "comprising," strike out all to and including the word "and" in line 78; and that the said Letters Patent should be read with these corrections therein that the same may conform to the record of the case in the Patent Office.

Signed and sealed this 13th day of June, A. D., 1922.

[SEAL.]

KARL FENNING,
Acting Commissioner of Patents.
